[57] CLAIM

The ornamental design for a zipper pull, substantially as shown and described.

DESCRIPTION

FIG. 1 is a front elevational view of a zipper pull showing my new design, the rear elevational view is a mirror image thereof;

FIG. 2 is a top view thereof;

FIG. 3 is a bottom view thereof;

FIG. 4 is a right side elevational view thereof, the left side elevational view is a mirror image thereof; and

FIG. 5 is a perspective view thereof.
